UNITED STATES PATENT OFFICE.

WILLIAM H. CLARKE, OF OLEAN, NEW YORK.

END-GATE FOR WAGONS.

SPECIFICATION forming part of Letters Patent No. 309,767, dated December 23, 1884.

Application filed March 26, 1884. (No model.)

To all whom it may concern:

Be it known that I, WILLIAM H. CLARKE, a citizen of the United States, residing at Olean, county of Cattaraugus, and State of New York, have invented new and useful Improvements in 5 End-Gates for Wagons, Cars, Trucks, Sleighs, &c., of which the following is a specification.

This invention relates to fastening devices for end - boards or tail - gates of wagons, cars, 10 trucks, sleighs, and other boxes used for storage and transportation purposes.

The essential objects of the invention are to lock a detachable end board or gate firmly 15 to the side-boards of the wagon or truck body, and prevent the rattling and vertical displacement thereof by the jolting or jarring of the wagon; to provide simple and effective means for operating the locking devices carried by 20 the wagon or other box, and hold the same in secure engagement with interlocking devices 25 fitted on the end - board; furthermore, to locate and construct the end-gate-fastening devices in such a manner that they will not project beyond the customary cleats between 30 which the end-board slides, thus placing said devices out of contact with the loaded articles 35 on the wagon when the end-gate is removed; and, finally, to properly guide the movement of the locking devices carried on the wagon or other body, and hold the same firmly locked when the end-gate is removed, in order to prevent the rattling displacement.

I attain the above results by the construction and arrangement of devices which will 40 be hereinafter more fully described, and then set forth in the claims.

In the drawings, Figure 1 is an elevation of a wagon-box, showing an end - gate locked in place by my improved fastening devices. 45 Fig. 2 is a view showing the end-gate removed and the shiftable locking - bars projected beyond the guide-cleats on the wagon-box. Fig. 3 is a vertical transverse section of a wagon-box end-gate and fastening devices. Fig. 4 is a detail view of the slotted cam - lever for 50 operating the shiftable locking-bar. Fig. 5 is a detail view of said locking - bar. Fig. 6 is a face view of the end - gate with the end slotted bar that engages with the shiftable 55 locking-bars on the wagon-box. Fig. 7 is a sectional view of said slotted bar. Fig. 8 is a

a detail view of the face-plate on the wagon-box, having a guide sleeve or socket for the shiftable locking - bar and Fig. 9 is a plan view of a portion of the box. Fig. 10 is modification of bar E.

The letter A designates so much of a wagon, car, sleigh, or other body or box as is necessary to show the manner of fitting and holding in position the vertically - sliding and removable end-board or tail - gate B. Vertical cleats a, secured to the inner sides of the side-boards of the wagon or other box in the customary manner, constitute guideways in which the end-board is seated so as to slide freely 60 up and down when it is in an unlocked condition. At the sides of the wagon or other box are located eccentric or cam levers C, which are fulcrumed or hung on horizontally - shiftable locking-bars D, that move through 65 the side-boards of the wagon-box and operate in the guideways for the end-board, formed by the vertical cleats a. These levers C are each provided with a cam - head having a slot, e, which virtually causes said head to consist of 70 two cheek-plates, between which the locking-bar D is fitted, a pivot or fulcrum pin or bolt, d, passing transversely through said cheek-plates and the locking-bar, serving to connect 75 these parts. The inner end of each locking-bar D terminates in a vertical hook, D', and at the base of said hook is formed an offset, D'', for the object hereinafter stated.

The above devices co-operate with an interlocking bar, E, fitted on the outer side or face 80 of the end-board or tail-gate, as is shown in Fig. 6. The bar E extends through vertical cleats or strips b², secured to the end-board, and has a limited sliding movement in said cleats, it being understood that the end portions, e², of said bar E are provided with vertical slots e³, which extend to the ends of the bar, where they terminate in top and bottom grooves, e⁴, formed by a small solid portion, e⁵, of the bar E, as is shown in Fig. 7.

It is evident that, when the hooked locking-bars D are in the projected state shown in Fig. 2, the slotted bar E is, by the descent of the end board or gate between the guide-cleats a, caused to receive the hooked ends of said 90 bars D, and the downward movement of the cam-levers C, fulcrumed on said bars, will 95

effect the drawing of the bars D in an outward direction from the end-board. In consequence thereof it will be seen that the hooks on the bars D are caused to interlock with the ends of the bar E, and that the pressure of the cam-heads upon the wagon or other box will serve to hold the parts in a securely-locked position.

The interlocking of the above parts in the described manner being at right angles to the points from which the force is exerted that would by the jolting of the wagon effect the vertical displacement of a tail-gate or end-board, it follows that no lifting action or force will effect the throwing out of position of the end-board after it has been locked in position.

It should be stated that one of the guide-cleats *a* on each side of the wagon-box is reduced in thickness at its upper end, and that the hooked locking-bars D operate against or in line with said reduced portions. The object of this conformation is to bring the locking-bars beyond the space occupied by the end-gate, and allow said bars to properly enter the slotted bar carried by the end-gate.

In order to cause the locking-bars to be drawn in a true line through the side-boards, I fit in the latter a metal sleeve or socket, G, which forms an integral part of a vertical face-plate, H, secured to the outer sides of the wagon-box by means of screws or other appropriate fastening devices. It will thus be seen that these face-plates, with their sockets, serve for the proper guidance and support of the hooked locking-bars.

It has already been stated that the cam-heads of the operating-levers are slotted for the reception of the locking-bars, and it may be added that the latter are completely inclosed in said slotted heads when said levers are in the pendent position shown in Fig. 1, and the pressure of the cam-heads is being exerted upon the wagon or other box.

It is desirable that, when the wagon is used without an end-gate—for example, when lumber is being carried—no projections be left in the interior of the wagon-box to come in contact with the board, and for this reason I have made the locking-bars D of such a length that they can be drawn into the spaces between the guide-cleats for the end-board; and in order to prevent the rattling of the locking-bars, or prevent any play or vibrations thereof, I provide the offset D² at the base of each hook D'. The locking of the cam-levers against the wagon-box will cause the offsets to be pressed against the inner ends of the sleeves or sockets of the face-plates, through which the hooked bars operate for attaining the above-mentioned result.

In order to fit the end-gate in position when the locking devices are placed as last described, it is only necessary to raise the cam-levers, whereupon the hooked ends of the locking-bars are moved inwardly and caused to clear the solid or grooved ends of said bars and come in line with the slots in the latter.

The weight of the end-gate then causes it to drop into position, and it is locked by the action of the levers in the manner already described.

The interlocking bar may be made in two pieces—that is, the center portion omitted—and the end slotted pieces be rigidly constructed with the end-gate, as shown in Fig. 10.

I am aware that a vertically-sliding end-gate 75 has been provided with a rod having a hook at each end to engage an eye at the inner end of a bolt passing through the side of the vehicle-body in rear of the vertical groove in which the end-gate slides, the other or outer end of 80 said bolt having a female screw-thread receiving a male screw held in place by a plate, and having an attached lever-arm, whereby the male screw can be rotated and the eye of the female screw-bolt drawn outward and interlocked with the hook on the end of the rod carried by the end-gate. My invention improves such construction, in that a more simple and less expensive mechanism is provided, and I employ a cam-lever having a slot to 90 form cheeks, which embrace and are pivoted to the outer end of a flat sliding bar having a hook at its inner end to interlock with a slot in a bar carried by the end-gate. This permits a narrow slot to be cut through the side 95 of the vehicle-body for introducing the sliding locking-bar, after which the divided or slotted head can be pivoted to the outer end of the said locking-bar. Where a screw having a lever-handle is employed to secure the 100 end-gate, many objections exist, the prominent ones being that the screw-threads rapidly wear, the gate loosens by the constant jar-ring, and if the screw be operated with any force the threads strip off or become injured. 105 Besides, the inner eyed ends of the screws or other devices as heretofore employed project at all times beyond the cleats constituting the guideway for the end-gate, and hence become bent, broken, or displaced in loading or unloading the wagon.

I am also aware that pivoted cam-levers have been employed in connection with sliding bars having eyed inner ends to engage hooks on rods carried by the end-gate, and such, therefore, I do not claim.

Having thus described my invention, what I claim is—

1. The combination of an end-gate, B, sliding vertically in guideways on the body, a bar, E, on the gate having a longitudinal slot, *e*, at its end, the sliding locking-bar D, guided through the side of the body, and having at one end the hook D' and offset D², for confining the end-gate, the said offset interlocking 125 with the slotted bar to prevent vertical movement of the end-gate, and the cam-lever C, having the slot *e*, to form cheeks which embrace and are pivoted to the outer end of the locking-bar, substantially as described.

2. The combination of the body having vertical cleats *a* at its sides to form guideways,

the end-gate sliding vertically in the guide-ways, a bar, E, having a slot, e^2 , at its end, the horizontally-sliding locking-bar D, guided through the side of the body, between the 5 cleats attached to each side, and having a vertically-projecting hook to engage the slotted bar, said body-cleats serving to protect the hooked end of the locking-bar when the end-gate is removed, and the swinging cam-lever, 10 D, pivoted to the outer end of the locking-bar, substantially as described.

3. A fastening for a vertically-sliding end-gate, consisting of the bar E, having the end slot, e^2 , the face-plate H, constructed with the 15 lateral guide sleeve or socket G, a locking-bar, D, sliding through the sleeve, and having its inner end provided with a hook to interlock with the slotted bar at right angles to the point from which the force is exerted that 20 would effect vertical movement of the end-gate, and the swinging cam-lever C, bearing on the face-plate, and having a slot, c, receiv-

ing and pivoted to the outer end of the locking-bar, substantially as described.

4. A fastening for vertically-sliding end-gates, consisting of the bar E, having the end slots, e^2 e^2 , the horizontally-sliding locking-bar D, having at its inner end a hook, D', and an offset, D'', for interlocking with the slots of the bar at right angles to the point from which the force is exerted that would effect vertical displacement of the end-gate, a swinging cam-lever having a slot, c, and pivoted to the outer end of the locking-bar, and the plate H, having the lateral sleeve G, substantially as 35 described.

In testimony whereof I have hereunto set my hand in the presence of two subscribing witnesses.
